UNITED STATES PATENT OFFICE.

CHARLES W. WIPFLER, OF DETROIT, MICHIGAN.

DESIGN FOR A RESERVOIR FOR STOVES.

SPECIFICATION forming part of Design No. 28,708, dated May 24, 1898.

Application filed November 6, 1897. Serial No. 657,707. Term of patent 7 years.

To all whom it may concern:

Be it known that I, CHARLES W. WIPFLER, a citizen of the United States, residing in Detroit, county of Wayne, and State of Michigan, have invented and produced a new and original Design for a Water-Reservoir to be Attached to Stoves, of which the following is a specification, reference being had to the accompanying drawing, in which the drawing is 10 a perspective of the reservoir.

The two end plates are similar in shape and form, except that the one is a reverse of the other. Each of the end plates A is deeply concaved or dished and at the front side or 15 that side which generally lies nearest the stove curves in an arc from the extreme outer end to its point of meeting with the stove-plate to which the reservoir is attached. The vertical line along this face is nearly straight, 20 so that the corner is somewhat in the form of a section of a cylinder or section of an oval prism. At the rear of the dished end the plate curves in; but its vertical line is also somewhat curved, and at its bottom line the 25 plate also curves in and is broken into curves

or swelling bosses. The front lower corner drops somewhat below the rear lower corner.

The two end plates A are united by a cross-plate curved to conform to the back and lower edges of the end plate. The end plates, however, at their forward lower corners drop below and sustain the plate which forms the back and the bottom. 30

The top C of the reservoir is plain.

The leading feature of the design consists 35 in the deeply-dished end plates with their three incurving sides, especially the incurving lower edge, showing curves continuous at the front, bottom, and back and presenting at neither of these places an abrupt angular corner. 40

What I claim is—

A design for a reservoir for stoves, substantially as shown and described.

In testimony whereof I sign this specification in the presence of two witnesses. 45

CHARLES W. WIPFLER.
